REINHOLD H. WAPPLER, OF NEW YORK, N. Y.

INTERRUPTER APPARATUS.

No. 863,955.

Specification of Letters Patent.

Patented Aug. 20, 1907.

Application filed October 30, 1906. Serial No. 341,296.

To all whom it may concern:

Be it known that I, REINHOLD H. WAPPLER, a citizen of the United States, residing in the borough of Manhattan, city, county, and State of New York, have invented an Improvement in Interrupter Apparatus, of which the following is a specification.

Heretofore in the production of the so-called Tesla currents, an apparatus has been employed commonly comprising a spark coil, an armature mounted to revolve on a suitable axle, the axle being provided with a flattened portion or cam,—a spring, a pair of contact points, one being carried by the said spring which is actuated by the flattened portion of the said axle so that the contact points are separated by this flattened portion of the axle and brought together by the action of the spring, and a condenser which is charged by the sparks resulting from the breaking of the current at the contact points,—the discharges of the condenser being employed to produce the Tesla currents. Now heretofore in X-ray apparatus, for instance an electrolytic interrupter has commonly been employed, but I have found that by suitably arranging the circuits, a mechanical interrupter similar to that hereinbefore referred to in the production of the so-called Tesla currents,—may be employed with equally efficient results in an X-ray apparatus. In carrying out my invention therefore, I employ together with a suitable source of electricity, a mechanical interrupter, an electro-magnet for actuating the same, a Ruhmkorff coil whose primary winding is connected in multiple with the coil of the said electro-magnet and a condenser connected across the terminals of the contact points of the mechanical interrupter as will be hereinafter more particularly described.

In the drawing, Figure 1 is a diagrammatic illustration of my improved interrupter apparatus. Fig. 2 is a front elevation of the form of mechanical interrupter, Fig. 3 is a plan of the same, and Fig. 4 is an elevation of a modified form of armature.

Referring to the drawing, and particularly to Figs. 2 and 3,—*a* designates a base provided at both ends with an upright *b* journaled in and extending between which is a shaft or axle *c*. Secured in this axle *c* is an armature *d* and preferably a fly-wheel *d'*, and a portion of the axle *c* on opposite sides thereof may be flattened as indicated at 2.

e represents an upright through and at right angles to the shaft *c* an adjusting screw. *e'* passes, the end 3 of which forms one of the contact points at which an electric circuit may be broken, the other contact point 4 being carried on a suitable spring *g* secured to a block fixed on the base or otherwise and adapted to be engaged by the flattened portion of the axle *c* to separate the contact points 3—4, which return and contact with one another by the action of the spring when the axle *c* is in a position at 90° to that shown in the drawing.

It will be understood that a mechanical interrupter other than that hereinbefore described, may be employed without departing from the nature and spirit of my invention.

60

Referring particularly to Fig. 1, in which the mechanical interrupter is shown together with the other parts diagrammatically, *h* is an electro-magnet so placed that the core thereof is in alignment with the armature *d* at two points in its revolution.

65

i is the customary Ruhmkorff coil employed in X-ray apparatus, *l* a condenser and *m* a suitable generator or other source of electricity; the positive terminal of the generator *m* is connected through a suitable resistance *m'* with one terminal of the primary winding of the 70 Ruhmkorff coil by the wire 5 and the other end of the primary winding of the Ruhmkorff coil by the wire or connection 6 to the binding post 7 in electrical connection with the spring *g* and contact point 4, the contact point 3 being connected to the negative terminal of the 75 generator through the binding post 8 and wire 9.

From a junction point 10 in the wire 5, the wire 11 is taken and connected with one terminal of the coil of the electro-magnet *h*, the other end of the magnet coil being connected by a wire 12 with a binding post 7, 80 while the condenser *l* is connected across the contact points 3, 4 by the wires 13, 14, leading from its respective terminals to the binding posts 7, 8, it being understood that the wires 15 from the terminals of the secondary winding of the Ruhmkorff coil *i* lead to the terminals of the vacuum tube, as is customary in X-ray apparatus.

85

From the hereinbefore described arrangement of the devices comprising the X-ray apparatus, it will be understood that the electro-magnet *h* and the primary 90 winding of the Ruhmkorff coil are in multiple with one another and are both in series with the circuit through the contact points 3, 4, by means of which the circuit is interrupted. Now with the parts in the position shown in Fig. 1, the various circuits are open, in as much as the contact points 3, 4, are separated, and in order to close the circuit to energize the magnet *h* it is necessary to turn the armature *d* and its shaft *c* manually or otherwise, sufficiently to permit the contacts 3 4 to come together through the action of the spring *g*. The 100 point at which the contacts 3 4 come together is reached before the armature is turned 90 degrees, and the moment the current is closed through the magnet coil *h* the same is energized and imparts an impulse to the armature *d* tending to turn the same to the position shown in Fig. 1, but before reaching this position the contacts 3 4 are parted again through the cam action of the flattened portion of the axle against the spring *g* and the momentum of the armature carries the same over the magnetic dead center position shown in the drawing. When the circuit is closed through the magnet coil *h* it will also be closed in multiple therewith.

110

through the primary of the Ruhmkorff coil *i* thereby setting up an induced current in the secondary of the Ruhmkorff coil which is utilized by being discharged through a vacuum tube in X-ray work or otherwise as desired. Now as will be understood when the circuit through the primary of the Ruhmkorff coil is closed there will be a self induced current set up therein, which in view of the connections and circuits hereinbefore described will be discharged through the magnet coil *h*, energizing the same and thereby imparting an additional impulse to the armature *d* which increases the rapidity with which the same and the axle *c* revolve. The condenser *l* is employed as is customary, to absorb or reduce as far as possible, the 15 sparks between the contact points 3 4 in the breaking of the circuit.

I have found that the hereinbefore described straight bar two pole armature *d* is particularly adapted to low voltage work, say 10 volts or thereabouts, while at 20 higher voltages,—110 volts or thereabouts,—a three pole armature *d*², as shown in Fig. 4, may be employed to advantage. This manifestly is due to the fact that with the two pole armature, the period of make and break and consequently that of magnetization and demagnetization, are decidedly unequal, that is to say, the period of demagnetization is materially greater than the period of magnetization, whereas with an armature of three or more poles, the periods of make and break in the current are more nearly equalized, it being understood that in a given case the armature shaft is provided with as many flat sides against which the contact spring operates, as there are poles in the armature employed.

I claim as my invention:

35 1. In an interrupter apparatus, a source of electricity,

a pair of separable contacts, a revoluble means by which said contacts are separated, an electro magnet, means actuated by the electro magnet for operating the means for separating the contacts, a mechanical means for bringing the contacts together and a Ruhmkorff coil in circuit in multiple with the said electro magnet.

2. In an interrupter apparatus, a source of electricity, a pair of contacts, terminals therefor, a magnet, means operated thereby for separating said contacts and a Ruhmkorff coil whose primary winding is in multiple with the coil of the said magnet between the said source of electricity and the terminal of one of the said contacts, so that the coil of the magnet and the primary of the said Ruhmkorff coil are in multiple with each other when the circuit is closed by the said contacts and the coil of the 50 said magnet and the primary of the said Ruhmkorff coil are in series with each other when the circuit is broken at the said contacts.

3. In an interrupter apparatus, a source of electricity, an armature, an axle on which the said armature is mounted, an electro-magnet for actuating the axle through the said armature, contact points for making and breaking the circuit when the said axle is revolved and a Ruhmkorff coil whose primary winding is connected in multiple with the coil of the said electro-magnet.

4. In an interrupter apparatus, a source of electricity, an armature, an axle on which the armature is mounted, said axle being provided with a flattened portion, an electro-magnet for actuating the said axle through the said armature, a spring, a contact point carried by the said spring, 65 a fixed contact point, the said contact points being separated by the said flattened portion of the axle acting on the said spring, and a Ruhmkorff coil whose primary winding is connected in multiple with the coil of the said electro-magnet, the circuit through the said contact points 70 being in series both with the primary winding of the Ruhmkorff coil and the coil of the said electro-magnet.

Signed by me this 24th day of October, 1906.

REINHOLD H. WAPPLER.
